(57) CLAIM

The ornamental design for a container for cosmetics, as shown and described.

DESCRIPTION

FIG. 1 is a top plan view of a container for cosmetics showing my new design;

FIG. 2 is a bottom perspective view thereof;

FIG. 3 is a rear view of FIGS. 1 and 4;

FIG. 4 is right a side view thereof; and,

FIG. 5 is a front view thereof.

The broken lines which define the bounds of the claim on the top and bottom surface form no part thereof.
